UNITED STATES PATENT OFFICE.

DAVID T. LINEGAR, OF CAIRO, ILLINOIS.

CAR-COUPING.

SPECIFICATION forming part of Letters Patent No. 297,701, dated April 29, 1884.

Application filed March 21, 1884. (No model.)

To all whom it may concern:

Be it known that I, DAVID T. LINEGAR, a citizen of the United States, residing at Cairo, Alexander county, Illinois, have invented certain Improvements in Car-Couplings, of which the following is a specification.

My invention relates to that class of couplings in which the cars are coupled by means of links and pins passing through vertical openings in the draw-heads; and the main object is to provide a simple, cheap labor and life saving attachment which can be applied to the car-couplings now in common use, especially those of the freight-car pattern, to render the coupling of the cars automatic. This object I attain as more fully described hereinafter.

In the accompanying drawings, Figure 1 is a view or side elevation of a draw-head with my improved pin-support applied thereto. Fig. 2 is a similar view with the pin-support pushed back and the link and pin shown in coupled position. Fig. 3 is a side elevation of a common draw-head without my application. Fig. 4 is a sectional elevation, the supporting-head and telescopic tube with inclosed springs.

A is the supporting-head, upon which the pin rests; B, tube attached to head; C, tube at-

tached to filling-piece E; D, the spiral springs. 30 F is the open space in the common draw-head.

My invention may be applied to any of the draw-heads now in common use, cast or wrought iron, by a slight change in the supporting-head A to suit the draw-head to which it is to 35 be applied. The drawings, however, are taken from the wrought-iron draw-heads in common use, and the links and pins are the same as those in common use, and will couple cars when the draw-heads are of different heights, 40 as is now done by hand.

My attachment, as illustrated detached in Fig. 4, consists of the supporting-head or pin rest and support A; B, tube attached to head; C, tube attached to filling-piece E, and D the 45 spiral spring, and when in position are operated as shown in Figs. 1 and 2.

I claim as my invention—

The combination, with the draw-head, of the pin rest and link supporting head A, tube B 50 attached to head, tube C, attached to filling-piece E, and the spiral spring D, as shown and described.

DAVID T. LINEGAR.
